UNITED STATES PATENT OFFICE.

RICHARD D. BRACE, OF NASSAU, NEW PROVIDENCE, BAHAMA ISLANDS.

DESIGN FOR A COMBINATION-TOOL.

53,352.

Specification for Design.

Patented May 27, 1919.

Application filed January 18, 1916. Serial No. 72,867. Term of patent 14 years.

To all whom it may concern:

Be it known that I, RICHARD D. BRACE, a subject of the King of Great Britain, residing at Nassau, New Providence, Bahama Islands, West Indies, have invented a new, original, and ornamental Design for Combination-Tools, of which the following is a specification, reference being had to the accompanying drawing, forming part thereof.

The figure is a perspective view of the combination tool, showing my new design.

I claim:

The ornamental design for a combination tool, as shown.

RICHARD D. BRACE.
